GOVERNOR COMPENSATOR

Howard D. Green, Compton, Calif., assignor to MacClatchie Manufacturing Company of California, Compton, Calif., a corporation of California

Application May 22, 1939, Serial No. 274,994

2 Claims. (Cl. 264—8)

My invention relates to a means of compensating the conventional governor.

The object of my invention is to provide the conventional governor with a compensating mechanism in order to secure a more sensitive control of the engine speed than is possible by means of the conventional governor alone. This is done by means of a compensating mechanism which permits the governor to control the throttle in such a manner that the engine operates at a desired speed regardless of changes in the load. The governor is provided with a pair of governor arms, and as said governor arms swing they close a circuit inducing electrical energy in the compensating mechanism, thereby opening or closing the throttle within much more definite limits than is possible by means of the conventional governor alone.

In other words, if a change is made in the load on the engine, the governor through the compensating mechanism operates the throttle so that the engine carries the load without a change in engine speed, whereas without the use of my invention, the conventional governor alone would operate the throttle so that the engine would carry the load, but only with a change in engine speed.

My invention has many other objects, advantages, and features, some of which, with the foregoing, will be set forth at length in the following description where I shall outline one form of my invention, which I have selected for illustration in the drawings accompanying and forming a part of the present specification. It is to be understood that I do not limit myself to the form shown in the drawings which has been selected for purposes of illustration since the invention, as expressed in the claims, may be embodied in a large plurality of forms.

Referring to the drawings:

Figure 1 is a front elevation of an engine provided with the governor compensating mechanism of my invention.

Figure 2 is an enlarged side elevational view, partly in section, of the governor compensating mechanism shown in Figure 1.

In the drawings, the numeral 9 indicates an engine, provided with a throttle 10 having an arm 11, and a conventional governor 12. The governor compensating mechanism is obviously adapted to be used in connection with any type of governor and with any type of engine. For purposes of illustration I have described it in connection with a radial type of engine, such as shown and described in U. S. Patent No. 2,074,702

which was granted to John W. MacClatchie on March 23, 1937.

Although the governor may be of any type, the governor 12 as shown is of the said centrifugal type driven by the engine 9, the governor weights actuating the governor control shaft 13 to increase or decrease the energy supplied to the engine. Mounted on the governor control shaft 13 are governor arms 14 and 15. The governor arm 14 is connected to drag-link 16, and the other end of the drag-link 16 is connected to a pivoted arm 17. The upper end of the pivoted arm 17 is provided with contact points 18 and 19 which are adapted to contact points 20 and 21 respectively of movable arms 22 and 23 respectively. The movement of arms 22 and 23 is limited inwardly by stops 24 and 25 respectively. The movable arms 22 and 23 are adapted to be returned to the position shown in the drawings by means of spring 26 when said movable arms are not in contact with pivoted arm 17.

The governor arm 15 is connected to the throttle arm 11 by means of drag-links 30 and 31 and compensating link 32 which link is adapted to be moved by the compensating mechanism generally indicated by the numeral 38 in housing 39. The compensating link 32 is pivotably mounted on compensating screw-block 33 by means of the pivotal support 40. The compensating screw-block 33 is mounted on compensating screw 34 which is adapted to be rotated by the reversible motor 35, causing the compensating screw-block 33 to move along the compensating screw 34 depending upon the direction of rotation of the reversible motor 35.

The reversible motor 35 is connected to a source of electrical energy as indicated at 36, and to contact points 18, 19, 20 and 21 by means of electrical conduits 42, 41 and 43 respectively. Circuit-breakers 37 which are connected to the reversible motor by electrical conduits 44 are also provided in order to limit the travel of the compensating screw-block 33 on the compensating screw 34.

Upon a speed change, due to increase or decrease of load, the governor 12 directly actuates the throttle control 10 through arm 15, drag links 30 and 31, compensating link 32, which is pivotably mounted on the pivotal support 40 of compensating screw-block 33, and arm 11. The governor 12 also actuates the throttle control 10 through arm 14 and the compensating mechanism to open or close the throttle an additional amount to compensate for the drop in speed of the prime mover, due to the fact that the

governor cannot of itself hold the throttle open sufficient to take care for an increased load without there being an actual drop in speed. The compensating mechanism permits the prime mover to return to its original speed, while carrying the increased load.

As the governor arm 14 swings to the left due to increase of load, the drag link 16 and pivoted arm 17 are moved to the left, thereby causing contact points 18 and 20 to contact and close the circuit with reversible motor 35 by means of conduits 41 and 42. As this circuit is closed, electrical energy is induced, which energizes the reversible motor 35 causing said motor and the compensating shaft 34 to rotate.

As the shaft 34 rotates the compensating screw-block 33 on which the compensating link 32 is pivotably mounted travels along the shaft causing said link 32 to pivot about the link 30 acting as a fulcrum, moving the drag-link 31 and the throttle arm 11 to the right thereby opening the throttle 10. The engine 9 will now pick up to its original speed, and after said speed is attained, the governor arm 14 will move to the right thereby moving drag-link 16 and pivoted arm 17 to the right, causing contact points 18 and 20 to separate, thereby breaking the circuit and stopping the rotation of the reversible motor 35 leaving the throttle 10 in position to take care for the new load while the prime mover runs at its original speed.

As the governor arm 14 swings to the right due to decrease of load the drag line 16 and pivoted arm 17 are moved to the right, thereby causing contact points 19 and 21 to contact and close the circuit with reversible motor 35 by means of conduits 42 and 43. As this circuit is closed, electrical energy is induced, which energizes the reversible motor 35 causing said motor and the compensating shaft 34 to rotate in a direction opposite to the direction of rotation of said motor and said compensating shaft when the contact points 18 and 20 were in contact.

As the shaft 34 rotates, the compensating screw-block 33 on which the compensating link 32 is pivotably mounted travels along the shaft causing said link 32 to pivot about the link 30 acting as a fulcrum 34 moving the drag-link 31 and the throttle arm 11 thereby closing the throttle 10. The engine 9 will then decrease to its original speed, and after said original speed is attained, the governor arm 14 will move to the left thereby moving drag-link 16 and pivoted arm 17 to the left, causing contact points 19 and 21 to separate, thereby breaking the circuit and stopping the rotation of the reversible motor 35 leaving the throttle 10 in position to take care for the new load while the prime mover runs at its original speed.

When the circuit is broken by means of contact with either of the circuit-breakers 37, the throttle 10 is adapted to be operated by the governor arm 15.

The spring 26 allows the movable arms 22 and 23 to swing outwardly from stops 24 and 25 respectively when the governor arm 15 operates the throttle 10 directly when large variations of load are applied.

From the foregoing description taken in connection with the accompanying drawings, the uses, advantages, and operation of my invention will be readily understood by those skilled in the art to which the invention appertains. While I have described the principle of operation together with the form of my invention which I now consider to be the best embodiment thereof, I desire to have it understood that the articles shown are merely illustrative and that the invention is not to be limited to the details disclosed herein, but is to be accorded the full scope of the appended claims.

I claim:

1. The combination of an engine having a throttle, a governor adapted to operate said throttle, and a compensating mechanism operated by said governor, said compensating mechanism comprising a screw, a compensating member adapted for reciprocal movement on said screw, said compensating member being directly connected to said governor and to said throttle, and a member having contact points operatively connected to said governor, one of said contact points being adapted to close a circuit including a reversible motor which is adapted to rotate said screw in one direction when the load on said engine is increased and the other of said contact points being adapted to close a circuit including said reversible motor which is adapted to rotate said screw in the opposite direction when the load on said engine is decreased.

2. The combination of an engine having a throttle, a governor adapted to operate said throttle by means of connecting members, and a compensating mechanism operated by said governor to permit the engine to return to its original speed when the load on said engine is changed, said compensating mechanism comprising a screw, a compensating member adapted for reciprocal movement on said screw, one of said connecting members between the governor and the throttle being pivotably mounted on said compensating member and a member having contact points operatively connected to said governor, one of said contact points being adapted to close a circuit including a reversible motor which is adapted to rotate said screw in one direction when the load on said engine is increased and the other of said contact points being adapted to close a circuit including said reversible motor which is adapted to rotate said screw in the opposite direction when the load on said engine is decreased.

HOWARD D. GREEN.
